UNITED STATES PATENT OFFICE

153,861

DESIGN FOR A DISPENSER FOR POWDERED MATERIALS

John F. De Sales, Kew Gardens,
Long Island, N. Y.

Application March 25, 1947, Serial No. 137,867

Term of patent 7 years

(Cl. D52—2)

To all whom it may concern:

Be it known that I, John F. De Sales, a citizen of the United States, residing in Kew Gardens, Long Island, county of Queens, city and State of New York, have invented a new, original, and ornamental Design for a Dispenser for Powdered Materials, of which the following is a specification, reference being had to the accompanying drawing, forming part thereof.

Fig. 1 is a top plan view of a dispenser for powdered materials, showing my new design;

Fig. 2 is a front elevation of the same; and

Fig. 3 is a side elevation.

I claim:

The ornamental design for a dispenser for powdered materials, as shown.

JOHN F. DE SALES.
